UNITED STATES PATENT OFFICE.

FREDERICK MESINGER, OF NEW YORK, N. Y.

SADDLE FOR MOTOR-CYCLES.

1,115,711.

Specification of Letters Patent.

Patented Nov. 3, 1914.

Application filed April 22, 1914. Serial No. 833,588.

To all whom it may concern:

Be it known that I, FREDERICK MESINGER, a citizen of the United States, residing at New York city, county of Bronx, and State 5 of New York, have invented a new and useful Improved Saddle for Motor-Cycles, of which the following is a specification.

This invention relates to a saddle more particularly adapted for motor cycles, which 10 is so constructed that jolts are freely taken up by means of coiled springs which are pneumatically cushioned, so that in this way a pleasant riding is insured.

In the accompanying drawing: Figure 1 15 is a longitudinal section partly in side view of a saddle embodying my invention; Fig. 2, a cross section thereof, and Fig. 3, a top view of the cylinders and adjoining parts, with the nuts removed and the bails in sec- 20 tion.

To the cantle 10, of the saddle top 11, are secured a pair of brackets 12, which are ap- 25 pertured for the reception of bolts 13. These bolts serve to sustain the rear end of the stay spring 14 and also for attachment to the cantle of a pair of knuckles or eyes 15. Through these knuckles pass loosely the upper horizontal members of a pair of bails 16, the lower hook-shaped ends of which en- 30 gage apertures formed in the upper portions of a pair of cylinders 17. These cylinders are closed by heads 18, and are by the construction described, so suspended from the back of the saddle top that they have a free 35 pivotal movement, and will at the same time participate in any vertical action of said top.

The seat post 19 is straddled by a resilient yoke 20, having a pair of corrugated or roughened cheeks that are engaged by a pair 40 of correspondingly shaped plates 21. These plates have upper and lower flanges and accommodate the two parallel members 22 of the seat frame, to the forward end of which the front of the saddle top 11 is secured, 45 while the back part of said top is freely suspended above said members. A bolt 23, passing through the members 22 as well as through plates 21 and yoke 20, so secures the seat frame to post 19, that the dip of the 50 former may be readily adjusted. Yoke 20 is provided at its lower end with a pair of opposed integral jaws 20^a that upon abutting with each other, will prevent any such undue contraction of the yoke, as would 55 throw its cheeks out of parallelism, which would involve a loosening of the seat frame

connection. The rear ends of members 22 are deflected laterally to form diverging arms 24, each of said arms, terminating in an eye 25. This eye encompasses the upper 60 end of a piston or plunger rod 26, which extends into cylinder 17 and is fixedly secured to arm 24 by a nut 27. Rod 26 is encompassed by a spiral spring 28 which is housed in cylinder 17, and bears with its upper end against head 18, where it is engaged by nicked ends 16^a of bail 16. At its lower end 65 spring 28 bears against a plunger head 29, carried by rod 26. This plunger head, is preferably composed of a pair of disks be- 70 tween which a cup-shaped packing 30, is interposed, so that in this way a substantially air tight joint is formed between cylinder and plunger.

It will be seen that by the construction de- 75 scribed, the plungers are maintained by the seat frame in a permanent or fixed position, while on the other hand, the cylinders will participate in the movement of the seat. Thus when owing to an obstruction on the 80 road, the seat descends, the cylinders 17 will participate in this movement, which move- 85 ment is cushioned by the joint action of springs 28 and plungers 29, the parts 17, 29 acting in the manner of a dash pot. Upon the subsequent cessation of excessive pres- 90 sure on the seat, the springs will again raise it to its normal position, in which action the springs are assisted by the previously gen- 95 erated overpressure and underpressure respec- tively created above and below plunger 29. By the construction described the springs are not only properly housed, but sudden and heavy jolts of the seat are effectively overcome, so that an easy riding free from violent or unpleasant shocks is insured. 95

I claim:

1. A saddle provided with a seat frame, a saddle top carried thereby and having a freely movable rear part, a pair of cylinders 100 depending from said rear part, a pair of pistons secured to a fixed portion of the seat frame and received by said cylinders, and a pair of coiled springs accommodated within the cylinders and engaging the pistons. 105

2. A saddle provided with a seat frame, a saddle top carried thereby and having a freely movable rear part, a pair of cylinders depending from said rear part, a pair of pistons secured to a fixed portion of the seat 110 frame and received by said cylinders, and a pair of coiled springs accommodated within

the cylinders and engaging the pistons, said pistons engaging the cylinders in a substantially air tight manner.

3. A saddle provided with a seat frame having diverging rear ends, a saddle top carried by the frame and having a freely movable rear part, a cantle on said rear part, a pair of bails pivoted to the cantle, a pair of cylinders pivoted to the bails, a pair of

pistons carried by the diverging ends of the seat frame and received by said cylinders, and a pair of coiled springs accommodated within the cylinders and engaging the pistons.

FREDERICK MESINGER.
